BEVERAGE DISPENSER OR SIMILAR ARTICLE

James R. Reichow, Edina, Minn., assignor to The Cornelius Company, a corporation of Minnesota

Filed July 10, 1964, Ser. No. 80,804

Term of patent 14 years

(Cl. D2—3)

FIG. 1 is a front perspective view of a beverage dispenser showing my new design.

FIG. 2 is a rear perspective view thereof.

Each of the lateral sides of the design is a reverse image of the other lateral side.

The dominant features of my design reside in the full lines.

I claim:

The ornamental design for a beverage dispenser or similar article, substantially as shown and described.
